UNITED STATES PATENT OFFICE

2,049,485

RAILWAY TRAFFIC CONTROLLING
APPARATUS

Earl M. Allen, Swissvale, Pa., assignor to The
Union Switch & Signal Company, Swissvale,
Pa., a corporation of Pennsylvania

Application June 23, 1931, Serial No. 546,237
Renewed April 28, 1932

20 Claims. (Cl. 246—3)

My invention relates to railway traffic controlling apparatus, and particularly to apparatus of the type involving a railway track switch and signals governing traffic over the switch.

More specifically, my invention relates to the approach locking of a switch, and has for an object the provision of novel and improved approach locking means whereby momentary release of the track relay for the section including the switch will not result in false operation of the approach locking apparatus.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a stretch of main railway track Y which is connected with a siding Z by means of a switch F. Main track Y is divided by insulated joints 2 into a switch section B—C containing switch F, and two approach sections A—B and C—D. Each of these sections is provided with a track circuit comprising a track battery 3 connected across the rails adjacent one end of the section and a track relay T, with a distinguishing exponent, connected across the rails adjacent the other end of the section.

Signals designated by the reference characters S¹ and S², respectively, govern traffic movements over switch F in the eastbound direction, that is, toward the right as shown in the drawing. Signal S¹ governs traffic movements along main track Y over switch F in its normal position in which it is shown in the drawing, whereas signal S² governs traffic movements from track Y to siding Z over switch F reversed. As here shown, signals S are of the semaphore type.

Switch F may be operated between normal and reverse positions by any suitable electrically controlled mechanism E. A pole-changer P having contacts 9 and 10 is operated in conjunction with switch mechanism E so that when switch F is moved to its normal position, pole-changer P causes electric current to be supplied in a normal direction, from a source not shown in the drawing but having terminals x and o, for energizing a polarized switch indication relay K in the normal direction. When switch F is operated to its reverse position, pole-changer P causes current to be supplied in the reverse direction for energizing relay K in the reverse direction.

Switch operating mechanism E is controlled

in a well known manner by a neutral contact 39 and polar contacts 40 and 41 of a polarized switch control relay W. Relay W is, in turn, controlled by pole-changing contacts 18 and 21 of a manually operable switch lever V¹, and also by a front contact 19 of an approach locking relay M, as well as by a front contact 20 of track relay T² for switch section B—C.

Signals S¹ and S² are controlled by home relays H¹ and H², respectively. Relays H¹ and H² are controlled by normal and reverse contacts, respectively, of relay K and by a signal relay R as well as by track relay T², a back contact 34 of approach locking relay M, and a release relay designated by the reference character TEP.

Signal relay R is controlled by track relay T² and by a normally open contact 22 of a manually operable signal lever V².

Levers V¹ and V² may be placed together in some central location such, for example, as a train dispatcher's office.

Approach locking relay M has four pick-up circuits, the first of which includes front contact 15 of approach track relay T¹; the second of which includes back contact 25 of approach track relay T³, normal polar contact 26 and front neutral contact 27 of relay K as well as back contact 28 of relay T²; the third of which includes back contact 24 of release relay TEP, reverse polar contact 26, front neutral contact 27 of relay K as well as back contact 28 of relay T²; and the fourth of which includes contact 14 of a slow pick-up relay TE. Relay M has one stick circuit including its own front contact 16. This stick circuit and all four pick-up circuits include back contact 11 of relay R and front contact 12 of a signal back lock relay G. Back contact 29 of relay G completes a shunt path around the winding of relay M, when relay G is deenergized.

Relay G is controlled by back contacts 1 and 3 of signal home relays H² and H¹.

Slow pick-up relay TE is controlled by a front contact 30 of relay T² in multiple with a reverse polar contact 32 and a neutral front contact 31 of relay K, and by back contact 16 of relay M in series with front contact 12 of relay G and back contact 11 of relay R. Relay TE is of a type having a checking contact 6 which opens after relay TE has been energized for a given period as, for example, ten to fifteen seconds, and has a second contact 5 which opens after a further period of time. A third contact 14 of relay TE closes when contact 5 opens.

Release relay TEP is controlled by contacts 5 and 6 of relay TE in series.

As shown in the drawing, all parts are in their normal condition, that is, sections A—B, B—C, and C—D are unoccupied, switch F is in its normal position, signals S¹ and S² are indicating "stop", and levers V¹ and V² are in their normal positions. With switch F in its normal position, relay K is energized by current of normal polarity, causing its polar contacts 26 and 38 to be closed in the normal position and its contact 32 to be open. Relays H¹ and H² are deenergized, and hence relay G is energized by a circuit passing from terminal x, through contacts 7 and 8 of relays H² and H¹, respectively, and the winding of relay G to terminal o. With lever V¹ in its normal position, relay W is energized by current of normal polarity by a circuit passing from terminal x, through contact 21 to the left, winding of relay W, front contact 20 of relay T², front contact 19 of approach locking relay M, and contact 18 of lever V¹ to the left, and thence to terminal o. Approach locking relay M is energized by its first pick-up circuit passing from terminal x, through back contact 11 of relay R, front contact 12 of relay G, wires 13 and 13^a, contact 15 of relay T¹, wire 17, and the winding of relay M to terminal o. The stick circuit for relay M is also closed, following the pick-up circuit just traced as far as wire 13, thence passing through wires 13^b and 13^c, front contact 16 of relay M, and the winding of relay M to terminal o. With relay M energized, the circuit for relay TE is open at the back point of contact 16 of relay M. With relay TE deenergized, relay TEP is energized by a circuit passing from terminal x, through contacts 5 and 6 of relay TE, and winding of relay TEP to terminal o.

I will now assume that with all parts of the apparatus thus in their normal condition, the dispatcher desires to clear signal S¹ for traffic to move along track Y. He will therefore move lever V² to the left, completing a circuit for energizing relay R passing from terminal x, through contact 22 of lever V², front contact 23 of relay T², and the winding of relay R to terminal o. Relay R, upon becoming energized, opens its back contact 11 in the pick-up and stick circuits previously traced for relay M, and thus causes relay M to become deenergized. Relay M, upon becoming deenergized, opens, at its contact 19, the circuit previously traced for relay W. Relay W, upon becoming deenergized, permits its contact 39 to open, thereby interrupting the operating circuit for switch mechanism E so as to prevent operation of switch F. With relay R energized and with relay M deenergized, relay H¹ becomes energized by a circuit passing from terminal x, through front contact 33 of relay TEP, back contact 34 of relay M, front contact 35 of relay T², front contact 36 of relay R, front contact 37 and polar contact 38 of relay K in its normal position, and winding of relay H¹ to terminal o. Relay H¹, upon becoming energized, closes its contact 42, thereby completing an operating circuit for signal S¹ which causes the arm of signal S¹ to indicate "proceed". The energization of relay H¹ causes its contact 8 to open, thereby breaking the circuit for relay G and causing this relay to become deenergized. Relay G, upon becoming deenergized, permits its back contact 29 to close and thereby complete a shunt around the winding of relay M. This shunt protects against energization of relay M

from any stray current due to crosses or other causes.

An eastbound train, on entering section A—B, deenergizes approach track relay T¹, contact 15 of which then opens in one of the pick-up circuits previously traced for relay M, which with relay R energized for clearing signal S¹ and with relay G deenergized on account of relay H¹ being energized, is already open at contacts 11 and 12 of relays R and G, respectively. The train, upon entering section B—C, deenergizes relay T² which then, at its contact 23, opens the circuit for relay R. Contact 36 of relay R then opens the circuit for relay H¹, which causes signal S¹ to indicate stop. As the train proceeds further and enters section C—D, deenergizing relay T³, the second pick-up circuit will be completed for relay M passing from terminal x, through back contact 11 of relay R, front contact 12 of relay G, back contact 25 of relay T³, polar contact 26 in the normal position and front neutral contact 21 of relay K, back contact 28 of relay T², and the winding of relay M to terminal o. Relay M, upon becoming energized, will continue energized by its stick circuit if the dispatcher returns lever V² to its normal position before the train leaves section B—C.

I will now assume that after the train has left section C—D and all parts of the apparatus have been again returned to the normal condition, the dispatcher again clears signal S¹ for an eastbound train to move along track Y over switch F in its normal position. If then an eastbound train enters section A—B and if before the train passes signal S¹ the dispatcher should desire to reverse switch F, he will return lever V² to its normal position and move lever V¹ to the reverse position. Relay M having become deenergized on account of relay R being energized and relay G being deenergized will prevent relay W from at once being energized in the reverse direction. Lever V², upon being returned to its normal position, causes relay R to become deenergized and this in turn deenergizes relay H¹ and causes the arm of signal S¹ to return to the stop position. Relay H¹, upon becoming deenergized, completes the circuit for relay G which then closes its front contact 12. With relay R deenergized and relay G energized and with relay M deenergized, a circuit is now closed for energizing slow pick-up relay TE passing from terminal x, through back contact 11 of relay R, front contact 12 of relay G, wires 13, 13^a, and 13^c, back point of contact 16 of relay M, front contact 30 of relay T², and the winding of relay TE to terminal o. After the lapse of a predetermined period of time, contact 14 closes and thus completes the fourth pick-up circuit for relay M passing from terminal x, through back contact 11 of relay R, front contact 12 of relay G, wires 13 and 13^a, contact 14 of relay TE, wire 17, and the winding of relay M to terminal o. Relay M, upon becoming energized, opens, at the back point of its contact 16, the circuit for relay TE and closes, at the front point of its contact 16, its own stick circuit. Relay M, upon becoming energized, completes at its contact 19 the reverse energizing circuit for relay W passing from terminal x, through contact 18 of lever V¹ in its reverse position, contact 19 of relay M, contact 20 of relay T², winding of relay W, and contact 21 of lever V¹ in its reverse position to terminal o. The reverse energization of relay W causes its contacts 40 and 41 to become closed in the reverse position for supplying

operating current to switch mechanism E in the reverse direction. Mechanism E then moves switch F to its reverse position, whereupon relay K becomes energized in the reverse direction on account of the shifting of pole-changer P to its reverse position. The despatcher will now clear signal S² by reversing lever V² which then closes its contact 22 and completes the circuit previously traced for relay R. Relay R, upon becoming energized, opens its contact 11, thereby causing relay M to again become de-energized. With relay M deenergized, with relay R energized, and with relay K energized in the reverse direction, a circuit is now completed for energizing relay H² following the path previously traced for the circuit for relay H¹ as far as contact 31 of relay K, and thence passing through polar contact 38 of relay K in its reverse position, and the winding of relay H² to terminal o. Relay H², upon becoming energized, completes at its contact 43 the operating circuit for signal S², the arm of which then moves to the proceed position.

The train, upon entering section B—C, causes relay T² to become deenergized and open the circuit for relay R as previously described. The deenergization of relay R causes its contact 36 to open the circuit for relay H² which then, becoming deenergized, causes the arm of signal S² to return to the stop position. With relay H² now deenergized, relay G again becomes energized by its circuit previously traced. With relay R deenergized, with relay G energized, and with relay M deenergized, a second circuit is now completed for relay TE following the path previously traced for the first circuit for relay TE as far as back contact 16 of relay M, and thence passing through front contact 31 and reverse polar contact 32 of relay K, and the winding of relay TE to terminal o. Upon the lapse of a period of time which is shorter than the time required for contact 14 of relay TE to close, checking contact 6 of relay TE will open, thereby deenergizing relay TEP. Relay TEP, upon becoming deenergized, permits its back contact 24 to close. The third pick-up circuit for relay M is thereby completed, passing from terminal x, through back contact 11 of relay R, front contact 12 of relay G, wires 13, 13^b and 13^c, back contact 24 of relay TEP, polar contact 26 of relay K in its reverse position, front contact 27 of relay K, back contact 28 of relay T², and the winding of relay M to terminal o. If the despatcher returns lever V² to its normal position, thereby preventing the energization of relay R when the train leaves section B—C, relay M will then continue energized by its stick circuit previously traced.

If, with switch F reversed and with relay M deenergized on account of signal S² having been cleared, relay T² had in some way been momentarily deenergized instead of being deenergized by a train entering section B—C, relay M could not become energized because there would not be time enough for relay TEP to be deenergized and cause its back contact 24 to close on account of the opening of contact 6 of relay TE before contact 28 of relay T² in the third pick-up circuit for relay M again opened. If, on the other hand, switch F were in its normal position and relay M were deenergized due to the clearing of signal S¹, a momentary deenergization of relay T² could not cause relay M to become energized by its second pick-up circuit since it is

also necessary for relay T³ to be deenergized in order to complete the second pick-up circuit.

It follows that apparatus embodying my invention protects against an improper energization of relay M by a momentary deenergization of switch section relay T² if switch F is reversed as well as if switch F is normal. Apparatus embodying my invention, by means of the shunt completed around the winding of relay M through back contact 29 of relay G, also protects against false energization of relay M in any manner while either relay R or relay G is deenergized on account of the operation for clearing either signal S¹ or S².

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track switch, a signal for governing traffic movements over said switch, control means for said signal, a stick relay, a slow pick-up relay controlled by a back contact of said stick relay and having a contact which becomes opened only upon the lapse of a measured period of time after said slow pick-up relay becomes energized, a pick-up circuit for said stick relay controlled by said contact of the slow pick-up relay only when said switch is in a given position, a stick circuit for said stick relay controlled by said signal control means, and means controlled by said stick relay for controlling said switch.

2. In combination, a railway track switch, a signal for governing traffic movements over said switch, control means for said signal, a stick relay, a slow pick-up relay controlled by a back contact of said stick relay and having a contact which becomes opened only upon the lapse of a measured period of time after said slow pick-up relay becomes energized, a release relay controlled by a circuit which includes said contact of the slow pick-up relay, a pick-up circuit for said stick relay controlled by a back contact of said release relay, a stick circuit for said stick relay controlled by said signal control means, means controlled by a front contact of said release relay as well as by said signal control means for controlling said signal, and means controlled by said stick relay for controlling said switch.

3. In combination, a railway track switch, a signal for governing traffic movements over said switch, control means for said signal, a stick relay, a release relay controlled by a back contact of said stick relay, a pick-up circuit for said stick relay controlled by said release relay only when said switch is in a given position, a stick circuit for said stick relay controlled by said signal control means, and means controlled by said stick relay for controlling said switch.

4. In combination, a railway track switch, a signal for governing traffic movements over said switch, control means for said signal, a stick relay, a release relay controlled by a back contact of said stick relay, a pick-up circuit for said stick relay controlled by a back contact of said release relay only when said switch is in one given position, a stick circuit for said stick relay controlled by said signal control means, and means controlled by said stick relay for controlling said switch.

5. In combination, a railway track switch, a signal for governing traffic movements over said

- switch, control means for said signal, a stick relay, a slow pick-up relay controlled by a back contact of said stick relay and having a contact which becomes operated a measured period of time after said slow pick-up relay becomes energized and having a second contact which becomes operated after the lapse of a different period of time, a first and a second pick-up circuit for said stick relay controlled by said first and second contacts respectively of said slow pick-up relay, a stick circuit for said stick relay controlled by said signal control means, and means controlled by said stick relay for controlling said switch.
15. 6. In combination, a railway track switch, a signal for governing traffic movements over said switch, control means for said signal, a stick relay, a slow pick-up relay controlled by a back contact of said stick relay and having a contact which becomes operated a measured period of time after said slow pick-up relay becomes energized and having a second contact which becomes operated after the lapse of a different period of time, a pick-up circuit for said stick relay controlled by said first contact of the slow pick-up relay only when said switch is in one given position, a second pick-up circuit for said stick relay controlled by said second contact of the slow pick-up relay, a stick circuit for said stick relay controlled by said signal control means, and means controlled by said stick relay for controlling said switch.
20. 7. In combination, a railway track switch, a signal for governing traffic movements over said switch, control means for said signal, an approach locking relay, a pick-up circuit for said relay controlled by traffic adjacent said switch, a stick circuit for said relay controlled by said signal control means, a shunt formed across the winding of said relay when said signal control means is in condition for causing said signal to indicate proceed, and means controlled by said relay for controlling said switch.
25. 8. In combination, a section of railway track including a switch, a signal governing traffic movements over said switch, control means for said signal, an approach track section for said signal, a stick relay, a release relay controlled by a back contact of said stick relay, a track circuit for each of said sections including a track relay, a pick-up circuit for said stick relay including a back contact of each of said track relays when said switch is in its normal position, a second pick-up circuit for said stick relay including a back contact of said switch section relay and controlled by said release relay when said switch is in the reverse position, a stick circuit for said stick relay controlled by said signal control means, and means controlled by said stick relay for controlling said switch.
30. 9. In combination, a railway track switch, approach locking means for controlling said switch, a slow pick-up relay having a contact which becomes operated upon the lapse of a measured period of time after said slow pick-up relay becomes energized and having a second contact which becomes operated after the lapse of a different period of time, means for at times energizing said slow pick-up relay when said approach locking means is in condition for preventing operation of said switch, means controlled by said first contact for putting said approach locking means into condition to permit operation of said switch to a given position, and means controlled by said second contact for putting said approach
35. locking means into condition to permit operation of said switch to a second position.
10. In combination, a railway track switch, approach locking means for controlling said switch, a slow pick-up relay having a contact which becomes operated upon the lapse of a measured period of time after said slow pick-up relay becomes energized and having a second contact which becomes operated after the lapse of a different period of time, means for at times energizing said slow pick-up relay when said approach locking means is in condition for preventing operation of said switch, means controlled by said first contact for putting said approach locking means into condition to permit a given operation of said switch, and means controlled by said second contact for putting said approach locking means into condition to permit a second operation of said switch.
40. 11. In combination, a railway track switch, an approach track section for said switch, a signal adjacent the end of said section nearest said switch for governing traffic movements over said switch, locking means for at times preventing an operation of said switch while said signal indicates stop if said approach section is occupied, a time element device having a contact which becomes operated upon the lapse of a measured period of time after said time element device becomes energized and having a second contact which becomes operated upon the lapse of a different period of time after said time element device becomes energized, means for at times energizing said time element device if said signal is controlled to indicate stop, means controlled by said first contact for releasing said locking means to permit a given operation of said switch, and means controlled by said second contact for releasing said locking means to permit a different operation of said switch.
45. 12. In combination, a section of railway track including a switch, an approach section adjacent said switch section, a signal for governing the movement of traffic over the switch, locking means for preventing an operation of said switch if the signal is put to stop when said approach section is occupied, a time element device, means for energizing said time element device when the signal is put to stop, means controlled by said time element device for releasing said locking means to permit an operation of said switch upon the lapse of a measured period of time after said time element device becomes energized, and other means controlled by said time element device and operable only when the switch section is occupied for releasing said locking means, said other means becoming effective upon the lapse of a measured period of time after said time element device becomes energized.
50. 13. In combination, a section of railway track including a switch, an approach section adjacent said switch section, a signal for governing the movement of traffic over the switch, locking means for preventing an operation of said switch if the signal is put to stop when said approach section is occupied, a time element device, means for energizing said time element device when the signal is put to stop, means controlled by said time element device releasing said locking means to permit an operation of said switch upon the lapse of a measured period of time after said time element device becomes energized, and other means controlled by said time element device for releasing said locking means to permit an operation of said switch in one direction only, said

other means becoming effective only if the switch section is occupied at the end of a measured period of time after said time element device becomes energized.

14. In combination, a section of railway track including a switch, a manually controlled signal governed by traffic conditions in said switch section, locking means for at times preventing an operation of said switch, a time element device, means for energizing said time element device when the signal is manually put to stop, means controlled by said time element device for releasing the locking means to permit an operation of said switch upon the lapse of a given period of time after said time element device becomes manually energized, means for automatically energizing said time element device to initiate the release of said locking means when the signal is put to stop by a train entering said switch section provided the switch is in a given position only, and means controlled by said time element device and by the condition of occupancy of said switch section for completing the release of said locking means upon the lapse of a different period of time after said time element device becomes automatically energized.

15. In combination, a section of railway track containing a switch, locking means which if de-energized will prevent an operation of said switch, means including a time element device controlled by a train in said section for delaying the energization of said locking means until the lapse of a given interval of time after said train enters said section, manually controllable means for energizing said locking means, and means delaying the energization of said locking means for a different given interval of time after said manually controllable means is operated, provided there is a train approaching within a predetermined distance of said section.

16. In combination, a section of railway track containing a switch, locking means which if de-energized will prevent an operation of said switch, and means controlled by a train in said section and by said switch for delaying the energization of said locking means until the lapse of a given interval of time after said train enters said section if said switch occupies one but not the other of its extreme positions.

17. In combination, a section of railway track containing a switch, a signal for governing traffic movements over said switch, a signal relay controlled by a train in said section and also manually controlled for controlling said signal, locking means for controlling said switch, and means controlled by said signal relay and by said switch for causing energization of said locking means upon the lapse of a measured interval of time after a train enters said section if said switch

occupies one but not the other of its extreme positions.

18. In combination, a section of railway track containing a switch, a track circuit for said section including a track relay, locking means for controlling said switch, and means controlled by said track relay and by said switch for causing energization of said locking means upon the lapse of a measured interval of time after said track relay becomes deenergized if said switch occupies one but not the other of its extreme positions.

19. In combination, a section of railway track including a track switch for establishing a traffic route leading to an adjacent main track section or to a siding, depending upon the position of the switch, track circuits for the switch section and the adjacent section each having a track relay, approach locking means for at times preventing the operation of the switch, means for initiating the release of said locking means when a train enters said switch section, means for completing the release of said locking means when the switch position is such as to permit the train to enter said adjacent section comprising a circuit including in series a back contact of the switch section track relay and a back contact of the adjacent section track relay, and means for completing the release of said locking means when the switch position is such as to permit the train to enter the siding comprising a circuit including in series a back contact of the switch section track relay and a contact which becomes closed a measured time interval after such release is initiated.

20. In combination, a switch section of railway track containing a switch, an approach track section for said switch, a signal for governing the movement of traffic from said approach section to said switch section, an approach locking relay effective when deenergized to prevent operation of the switch, means for energizing said locking relay when the signal is manually put to stop provided said approach section is occupied, a time element device having a contact which is operated upon the lapse of a measured time interval after said time element device becomes energized and having a second contact which is operated upon the lapse of a different period of time after said time element device becomes energized, means controlled by the signal for at times energizing said time element device when the signal is put to stop, means controlled by said first contact for energizing said locking relay, and means controlled by said second contact effective only when the switch is in a given position for energizing said locking relay.

EARL M. ALLEN.
